DESIGN FOR A VEHICLE TIRE

George W. Anderson, Akron, Ohio, assignor to
The General Tire & Rubber Company, a corporation of Ohio

Application September 11, 1933, Serial No. 49,235

Term of patent 14 years

To all whom it may concern:

Be it known that I, GEORGE W. ANDERSON, a citizen of the United States, residing at Akron, in the county of Summit, and State of Ohio, have invented a new, original, and ornamental Design for a Vehicle Tire, of which the following is a specification, reference being had to the accompanying drawing, forming a part thereof.

The single figure in the drawing shows a perspective view of a tire embodying my design, a portion of the same being illustrated in dotted lines.

I claim:

The ornamental design for a vehicle tire, substantially as shown.

GEORGE W. ANDERSON.
